INTER-DENTAL JET PROPHYLACTIC DISPENSER

Garrison Trupp, 4600 York Road, Baltimore 12, Md.,
and Bernard Trupp, 913 Lake Drive, Baltimore 17,
Md.

Filed May 15, 1963, Ser. No. 74,886

Term of patent 14 years

(Cl. D24—1)

FIG. 1

FIG. 4

FIG. 5

FIG. 1 is a side elevation of an inter-dental jet prophylactic dispenser showing our new design.

FIGURE 2 is a front elevational view thereof.

FIGURE 3 is a rear elevational view thereof.

FIGURE 4 is a top plan view thereof.

FIGURE 5 is a bottom plan view thereof.

The side not shown is a mirror image of the side shown in FIGURE 1.

The dominant features of our new design are shown in solid lines in the drawing.

The container is omitted in FIGS. 2 to 5 inclusive for convenience of illustration only.

We claim:

The ornamental design for an inter-dental jet prophylactic dispenser, as shown and described.
